PROCESS FOR PRODUCING SUBSTITUTED
HYDROXY AROMATIC COMPOUNDSDonald R. Stevens, Wilkinsburg, Pa., assignor to
Gulf Research & Development Company, Pitts-
burgh, Pa., a corporation of DelawareNo Drawing. Application July 3, 1947.
Serial No. 758,987

5 Claims. (Cl. 260—624)

1

This invention relates to a process for producing substituted hydroxy aromatic compounds and more particularly to a process for producing hydroxy aromatic compounds bearing a substituent in a position on the nucleus other than the position which would be taken on direct substitution.

It is well known that the orientation of entering substituents into the nucleus of an aromatic compound depends upon the substituent groups already present in the aromatic nucleus. The groups attached to an aromatic nucleus fall into two classes, i. e., those which direct the next entering substituent to the meta position and those which direct the next entering substituent to the ortho and/or para positions. Substitution in the meta position of compounds having an ortho-para orienting influence and substitution in the ortho and/or para position of compounds having a meta orienting influence has long been accomplished by employing a blocking group. Likewise substitution in either the ortho or the para position of compounds having an ortho-para orienting influence has been accomplished by using a blocking group.

A variety of blocking groups have heretofore been used to obtain the desired orientation. Some of the blocking groups which have been used are the carboxyl group, the nitro group, and the sulfo group. The use of these blocking groups, however, has required complicated and relatively expensive operations. For example, when a nitro group is used as a blocking group to obtain a desired substitution, the nitro group is removed by a sequence of steps consisting of reduction, diazotization, and hydrolysis.

It is an object achieved by this invention to provide a process for producing hydroxy aromatic compounds bearing a substituent in a position on the nucleus other than the position which would normally be taken on direct substitution according to a simpler and more economical process than that of the past.

Another object achieved by this invention is to provide a process for producing hydroxy aromatic compounds in which a substituent is placed at a predetermined abnormal position on the aromatic nucleus.

A further object achieved by this invention is to provide a process which yields essentially only one isomer of a substituted hydroxy aromatic compound to the substantial exclusion of other isomers which normally are formed on direct substitution.

I accomplish these and other objects, which will become apparent as the description proceeds, by employing a tertiary alkyl group as a blocking agent. I have found that tertiary alkyl groups of from 4 to 12 carbon atoms are particularly desirable for the purpose of my invention.

2

Tertiary alkyl groups may be easily added to an aromatic nucleus. However, only under certain conditions may they be readily removed after the desired substitution has taken place without disturbing other substituents on the aromatic nucleus. A critical factor with respect to the removal of a tertiary alkyl group from an aromatic nucleus without affecting other nucleus substituents is that the aromatic nucleus must contain an hydroxyl radical.

In accordance with my invention the tertiary alkyl group or groups used for blocking must be oriented alkyl groups, i. e., the tertiary alkyl groups must occupy at least one of the positions to which an entering substituent would be directed if the tertiary alkyl group were not blocking that position. An oriented tertiary alkyl group then is one which occupies a definite spatial position relative to some other group or some other part of the aromatic nucleus. The term "oriented tertiary alkyl group" as used herein may therefore be defined as a tertiary alkyl group which is present on the ring in a position dictated by the orienting forces of the unalkylated compound. For example, in the alkylation of a meta directing compound such as nitrobenzene with isobutylene, a tertiary butyl group would enter the meta position thus forming meta-nitro-tertiary butylbenzene. In this case, the tertiary butyl group would occupy the "oriented" position with respect to the nitro group. On the other hand if tertiary butylbenzene were nitrated the nitro group would enter the para position and would be in an "oriented" position with respect to the tertiary butyl group. Thus, in accordance with my definition of an "oriented tertiary alkyl group," meta-nitro-tertiary butylbenzene contains an "oriented tertiary alkyl group" whereas para-nitro-tertiary butylbenzene does not contain an "oriented tertiary alkyl group."

In brief, the process of my invention includes the steps of alkylating an aromatic compound capable of exerting a directive influence upon a first entering tertiary alkyl group, substituting on the nucleus of the resulting alkylated aromatic compound a desired substituent, and thereafter dealkylating the substituted alkylated aromatic compound to give a substituted aromatic compound.

It should be understood that in practicing the process of my invention the alkylation step may be omitted in certain instances. For example, if suitably alkylated aromatic compounds are available then such compounds may be used as the starting material in the preparation of other compounds by substituting a selected group into one of the vacant positions on the aromatic nucleus followed by dealkylation to remove the tertiary alkyl group or groups which were originally

present. If, however, a suitably alkylated aromatic compound is not available, it may be prepared according to any means known in the art, such as alkylation, rearrangement of a tertiary alkyl aryl ether, etc. For the purpose of illustration of my invention I will hereinafter describe the first step as an alkylation step. Thus, the process of my invention comprises either preparing or selecting a tertiary-alkylated aromatic compound and treating this compound to form a substituted derivative, such that on removal of one or more of the tertiary alkyl groups the resulting compound will have substituents placed in relation to one another in a manner abnormal to that which would result from direct substitution in the unalkylated parent compound, or such that on removal of one or more of the tertiary alkyl groups a single isomer of an aromatic compound will be obtained to the substantial exclusion of several possible isomers which would be obtained by direct substitution in the unalkylated parent compound.

By "an aromatic compound capable of exerting a directive influence" upon a first entering tertiary alkyl group, I mean to include an aromatic compound having one or more of the following radicals as substituents: $(CH_3)_2N-$, R_2NCH_2- , H_2N- , $HO-$, $RO-$, $RCO NH-$, $RCOO-$, $HS-$, $RS-$, $R-$, $CICH_2-$, $-C_6H_5-$, $Cl-$, $Br-$, $I-$, $F-$, $-CH_2OH$, $HOOCH_2-$, $(CH_3)_3N-$, NO_2- , $N \equiv C-$, $-SO_2OH$, $-CHO-$, $-COR-$, $-COOH$, $-COOR$, and $-CONH_2$ where R is alkyl, alkenyl, aryl, cycloalkyl, alkaryl, or aralkyl and other substituted groups of the same general character.

It will be recognized that the above list does not include all of the radicals which exert a directive influence on substitution reactions. This list is given by way of example only and is not intended to impose any limitations on the scope of this invention.

Other aromatic compounds capable of exerting a directive influence upon a first entering tertiary alkyl group are naphthalene, indene, anthracene, fluorene, phenanthrene, and the like. Still other compounds capable of exerting an orienting influence upon entering tertiary alkyl groups fall into the class of heterocyclics, such as furan, thiophene, pyrrole, quinoline, indole, benzofuran, and the like.

The aromatic compounds which may be used as starting materials in accordance with the process of this invention fall into three general classes, namely: (1) aromatic compounds containing an hydroxyl radical, such as phenol, cresol, naphthol, etc., and substituted derivatives of these; (2) aromatic compounds containing a radical that is directly convertible into an hydroxyl radical, such as chlorobenzene, o-, m-, and p-chlorotoluene, chloroxylene, etc.; and (3) aromatic compounds not containing an hydroxyl radical or a radical that can be directly converted into an hydroxyl radical, such as toluene, xylene, naphthalene, anthracene, etc. The procedural steps, naturally, will vary depending upon the particular material chosen.

If phenol is chosen as the starting material for the preparation of 2,6-dichlorophenol my process may comprise the steps of butylation, chlorination, and debutylation as illustrated by Equation IV below. If chlorobenzene is chosen as the starting material for the preparation of o-cresol my process may comprise the steps of butylation,

methylation, hydrolysis, and debutylation as illustrated by Equation XI below. If toluene is chosen as the starting material for the preparation of o-cresol my process may comprise the steps of butylation, chlorination, hydrolysis, and debutylation as illustrated by Equation VI below.

According to a preferred embodiment of my invention, I use phenol or a substituted phenol as a starting material. However, I may use other substituted benzenes as represented by the formula:

15 *Fig. 1. Structure of a substituted benzene ring.*

where Y is one of the substituents as listed above.

Furthermore, more than one substituent may be present on the aromatic nucleus, provided that there are at least two vacant positions into one of which an entering substituent will be oriented.

Where an hydroxyl radical is not present in the starting material, one of the groups already present must be converted to an hydroxyl radical or an hydroxyl radical must be introduced by some other means prior to the dealkylation step. The process of my invention will hereinafter be described according to three major steps, i. e.

30 alkylation, substitution, and dealkylation. While the first major step includes alkylating an aromatic compound capable of exerting a directive influence upon a first entering tertiary alkyl group, it is to be understood that I do not wish to limit this invention in this respect inasmuch as I have pointed out above that I may use as a starting material an aromatic compound which already contains a tertiary alkyl group in a desired position.

40 The first major step of my process comprises alkylating an aromatic compound capable of exerting a directive influence upon a first entering tertiary alkyl group. The number of tertiary alkyl groups introduced into the nucleus of the aromatic compound depends upon the nature of the final product desired. For example, in the preparation of 2,6-dichlorophenol from phenol, it is necessary only to block the 4 position thus requiring only one tertiary alkyl group. In the preparation of 3-nitrophenol from phenol it would be necessary to block the 2, 4, and 6 positions thus requiring three tertiary alkyl groups.

45 Alkylation of the aromatic compound may be readily effected by contacting it with an alkylating agent, such as a tertiary olefin containing 4 to 12 carbon atoms per molecule in the presence of small amounts of an acid condensing agent, or even in some cases merely under heat and pressure. Other means of obtaining the alkylated compound may be employed without deviating from the scope of this invention. The alkyl group connected to the aromatic nucleus is a tertiary group, since I have found that tertiary alkyl groups are more easily removed without disturbing other substituents on the aromatic nucleus than are either normal or secondary alkyl groups.

50 Examples of the tertiary alkyl groups which I may use are tertiary butyl, tertiary amyl, diisobutyl, triisobutyl, and the like. In accordance with the preferred form of my invention I employ a tertiary butyl group because it is very easily removed to form isobutylene which can be recovered and used again for alkylation purposes. Furthermore, isobutylene itself is inexpensive

and is readily available in refinery gases such as those resulting from cracking operations.

When the substituent added in the second step of my invention is an alkyl group, it is important to choose as an alkylating material in the first step a tertiary alkyl group that is more easily removed than the alkyl group put on in the second step. Usually tertiary alkyl groups are more easily removed than primary or secondary groups. For example, if a normal amyl radical is added to an aromatic nucleus in the second step of my invention, I prefer to employ trimethylethylene or isobutylene as my alkylating material in the first step. Various condensing agents may be used in the alkylation step including aluminum chloride, zinc chloride, zirconium tetrachloride, ferric chloride, boron tri-fluoride, phosphoric acid, sulfuric acid, activated clays and the like.

The second major step of my process comprises substituting on the aromatic nucleus in at least one of the unoccupied positions of the alkylated aromatic compound produced in the first major step, an organic or inorganic radical depending upon the final product desired. Substitution is effected in a conventional manner under essentially the same conditions as would normally be employed for the unalkylated aromatic compound, except that dealkylating conditions must be avoided. For example, a chloro radical may be introduced by passing chlorine gas into a carbon tetrachloride solution of the alkylated aromatic compound at a temperature of about 0° C. Among the radicals which I may substitute on the alkylated aromatic nucleus are alkyl, aryl, aralkyl, acyl, alkenyl, haloalkyl, hydroxyalkyl, alkylaminoalkyl, carboxyalkyl, amino, amido, carbonyl, fluoro, chloro, bromo, iodo, nitro, sulfo, hydroxyl, mercapto, cyano, mercurio and other metallo radicals, and the like. The replacement of hydrogen on the nucleus of an aromatic compound with a radical such as a halo, nitro, sulfo, and the like may be accomplished by a direct substitution. Substitution of certain radicals, however, may require a more complex procedure. For example, the substitution of an hydroxyl radical on the nucleus of an aromatic compound such as toluene may require two separate reactions as illustrated hereinbelow by Equations VI, VII, and VIII. As exemplified by Equation VI, toluene may be alkylated with isobutylene to give 4,6-di-tert-butyltoluene. The 4,6-di-tert-butyltoluene is then chlorinated, the chlorine going into the open ortho position. The chloro-derivative is then converted by hydrolysis to an hydroxy compound, and the hydroxy compound is then dealkylated to give o-cresol. Instead of chlorination in Step 2a, I might have sulfonated. In this case, Step 2b would consist of alkali fusion to form the hydroxyl radical. Step 3 would then be debutylation. An alternate procedure would be to perform a nitration in Step 2a. The nitro radical attached to Step 2a could then be reduced in Step 2b to give the amino derivative; the amino derivative could then be converted to a diazonium salt, and treated with alcohol to form a substituted phenol, which on dealkylation would yield o-cresol.

It is therefore to be understood that in using the term "substitution" I am referring to a replacement of hydrogen on an aromatic nucleus by an organic or inorganic radical regardless of the number of separate reactions involved in adding a particular radical.

As mentioned above, if the particular starting

material chosen contains no hydroxyl radical, the dealkylation step of my invention must be preceded by an hydroxylation procedure. Thus, I have found that tertiary alkyl groups are easily removed from an aromatic nucleus when an hydroxyl radical is present on the aromatic nucleus. Accordingly, this invention is usefully applied to the preparation of substituted aromatic hydroxy compounds such as phenols, naphthols, anthranols and other polynuclear hydroxy compounds. Hydroxylation may be carried out according to conventional systems such as those hereinabove set forth. In some instances hydroxylation followed by dealkylation may be brought about by a single operation, such as in high-temperature catalytic hydrolysis of tertiary butylated chlorinated aromatic compounds.

The third major step of my process comprises dealkylating the substituted alkylated hydroxy aromatic compound produced according to the preceding steps of my invention. This step removes at least one of the tertiary alkyl groups added in step one to produce an hydroxy aromatic compound bearing a substituent in a position on the nucleus other than the position which would be taken on direct substitution without the aid of a tertiary alkyl blocking agent. As pointed out in the first major step above, the number of tertiary alkyl groups introduced into the nucleus of the aromatic compound depends upon the nature of the final product desired. Likewise, in the dealkylation step, the number of tertiary alkyl groups that I split off will depend upon the final product desired. Dealkylation may be readily effected by heating the substituted alkylated hydroxy aromatic compound in the presence of a dealkylation catalyst such as sulfuric acid, alkyl sulfuric acid esters, tetra-phosphoric acid, sulfonic acids, activated clays, metal oxides, aluminum chloride, or the molecular compounds of aluminum chloride with phenols, alcohols and the like. In the case of clays or metal oxides good results have been obtained by contacting the material to be dealkylated with the heated body of clay or metal oxide. Dealkylation is advantageously conducted at atmospheric pressure, although superatmospheric pressures and sub-atmospheric pressures may be used in some instances.

It will be understood that in using the term "dealkylation" I am referring to a splitting off of the oriented tertiary alkyl group or groups added during the first step of my process. Dealkylation in the contemplated manner does not split off such methyl, ethyl, or propyl or other primary or secondary alkyl groups as are present. By the term "dealkylation catalysts" as used herein, I mean clays and metal oxides or those compounds, usually of an acid nature, described hereinabove which when present even in relatively small amounts will cause a splitting off of the oriented tertiary alkyl groups added in the first step without substantial decomposition of the original aromatic compound and without affecting any substituent added in the second step of my process.

The process of my invention is commercially attractive in that the tertiary alkyl blocking group may be recovered and used over and over. Thus tertiary olefins, usually of high purity, may be recovered and recycled to the alkylation step. Accordingly, my invention may readily be carried out in a continuous manner with a distinct advantage.

The following equations illustrate the prin-

ciples of my invention but are not to be construed as limiting the same. These equations indicate the essential chemical reactions which take place and do not necessarily indicate all of the actual steps that would be used in preparing and isolating the compounds mentioned.

EQUATION I

4-isopropyl-m-cresol

(Step 1)—Butylation

(Step 2)—Propylation

(Step 3)—Debutylation

Direct propylation of m-cresol under conventional alkylating conditions produces a mixture of 2-, 4-, and 6-propyl-m-cresol.

EQUATION II

bis-(3-methyl-2-hydroxyphenyl) methane

(Step 1)—Butylation

(Step 2)—Condensation

(Step 3)—Debutylation

Direct condensation of o-cresol with formaldehyde would produce a mixture of bis-(3-methyl-2-hydroxyphenyl) methane, bis-(3-methyl-4-hydroxyphenyl) methane, and 2,4-dihydroxy-3,3'-dimethyl diphenylmethane.

droxyphenyl) methane, and 2,4-dihydroxy-3,3'-dimethyl diphenylmethane.

EQUATION III

o-Hydroxybenzoic acid (salicylic acid)

(Step 1)—Butylation

Normally the Kolbe-Schmitt synthesis with phenol itself yields a mixture of o- and p-hydroxybenzoic acid.

EQUATION IV

2,6-dichlorophenol

(Step 1)—Butylation

Direct chlorination of phenol would lead to the formation of 2,4-dichlorophenol.

EQUATION V

2,6-dihydroxy acetophenone

(Step 1)—Butylation

(Step 2)—Acylation

(Step 3)—Debutylation

Direct acetylation of resorcinol yields mainly 2,4-dihydroxy acetophenone.

EQUATION VI

o-Cresol

(Step 1)—Butylation

(Step 2a)—Chlorination

(Step 2b)—Hydrolysis

(Step 3)—Debutylation

Direct monochlorination of toluene would give a mixture of o- and p-chlorotoluene which would lead to the formation of a mixture of o- and p-cresol.

EQUATION VII

5-methylresorcinol

(Step 1)—Butylation

(Step 2a)—Chlorination

(Step 2b)—Hydrolysis

(Step 3)—Debutylation

5-methylresorcinol

Direct dichlorination of toluene would give a mixture of 2,4- and 2,6-dichlorotoluene leading to the formation of a mixture of 2,4-, and 2,7-dihydroxy derivatives instead of the 3,5-compound.

EQUATION VIII

2,3-dimethylphenol

(Step 1)—Butylation

(Step 2a)—Chlorination

(Step 2b)—Hydrolysis

(Step 3)—Debutylation

Direct monochlorination of orthoxylene would give a mixture of 3- and 4-chloro orthoxylene leading to the formation of a mixture of 2,3- and 3,4-dimethylphenol.

EQUATION IX

Pyrogallol

(Step 1)—Butylation

(Step 2a)—Chlorination

(Step 2b)—Hydrolysis

(Step 3)—Debutylation

Direct dichlorination of phenol would lead to the formation of 2,4-dichlorophenol which upon hydrolysis would yield a 1,2,4-trihydroxy benzene.

EQUATION X

Catechol

(Step 1)—Butylation

(Step 2a)—Chlorination

(Step 2b)—Hydrolysis

5

12

(Step 3)—Debutylation

10 Direct monochlorination of phenol would give a mixture of 2- and 4-chlorophenol which upon hydrolysis would give a mixture of catechol and hydroquinone.

15

EQUATION XI

o-Cresol

(Step 1)—Butylation

20

(Step 2a)—Methylation

25

(Step 2b)—Hydrolysis

30

(Step 3)—Debutylation

35

Direct methylation of chlorobenzene would lead to the formation of a mixture of o- and p-cresol.

40

EQUATION XII

o-Chlorophenol

(Step 2)—Chlorination

45

(Step 3)—Debutylation

50

45

55

60

65

70

75

13

Direct monochlorination of phenol yields a mixture of 2- and 4-chlorophenol.

Equations I, II, IV, V, X and XII illustrate that form of my invention wherein substitution is accomplished in a single step. Equations III, VI-IX and XI illustrate that form of my invention wherein at least two separate reactions are required to complete the desired substitution. In Equations IX and XI, Step 3, the debutylation step, might be performed prior to Step 2b since the compound already contains an hydroxyl radical. In Equation XII, Step 1 was omitted because the desired butylated phenol was used as a starting material.

A fuller and more complete understanding of my invention can be had through a consideration of the following examples which describe in detail the laboratory procedure followed in preparing certain specific compounds according to the process of my invention.

Example 1 corresponds to the reaction illustrated hereinabove by Equation IV.

Example 2 corresponds to the reaction illustrated hereinabove by Equation I.

Example 3 corresponds to the reaction illustrated hereinabove by Equation XII.

EXAMPLE 1

2,6-dichlorophenol

Into a flask provided with an agitator were placed 94 grams of phenol and 4.7 grams of concentrated sulfuric acid. The phenol-sulfuric acid mixture was maintained at a temperature of 70° C. and isobutylene was introduced slowly below the surface of the solution. The addition of isobutylene to the reactant mixture was continued until 56 grams of isobutylene had been absorbed. The product thus obtained was washed several times with water and then refluxed with a small amount of alcoholic KOH to neutralize the remaining acidic bodies. After washing again with water, the neutralized product was fractionated at atmospheric pressure through a 15 plate column. The temperature was increased up to 180° C. during which time a small amount of polymerized isobutylene was collected. The distillation system was then allowed to cool and placed under a pressure of 20 mm. of mercury. Fractionation was then continued whereby there was obtained a small amount of unreacted phenol boiling at 85° C. and a large amount of 4-tert-butylphenol boiling at 130° to 131° C. at 20 mm. pressure. This product had a melting point of 99° C.

136.3 grams of 4-tert-butylphenol made in accordance with the above procedure, together with 200 grams of carbon tetrachloride were placed in a flask excluded from light. The carbon tetrachloride solution of 4-tert-butylphenol was maintained at a temperature of about 0° C. and chlorine was introduced below the surface of the solution. The addition of chlorine to the reactant mixture was continued until 95.8 grams of chlorine were absorbed. The reaction product was then washed several times with 5 per cent aqueous sodium bisulfite to remove dissolved chlorine and with 10 per cent aqueous sodium bicarbonate to remove any hydrogen chloride still present. The product was then dried with anhydrous sodium sulfate and charged to a fractionating still having a column equivalent to 15 theoretical plates. After removing the carbon tetrachloride at atmospheric pressure, the remainder was fractionated into several fractions

14

at a pressure of 20 mm. of mercury, using a 10:1 reflux ratio. The fraction boiling at 150° to 152° C. at 20 mm. was determined to be 2,6-dichlor-4-tert-butylphenol.

The 2,6-dichlor-4-tert-butylphenol obtained as above was then dealkylated by passing it in a molten state through a Pyrex tube packed with 15 to 30 mesh Attapulgus clay maintained at a temperature between about 275° and 350° C. A white crystalline material melting at 64° to 65.5° C. was obtained. This material was determined to be 2,6-dichlorophenol.

EXAMPLE 2

4-isopropyl-3-methylphenol

Into a flask provided with an agitator were placed 108 grams of m-cresol and 5.4 grams of concentrated sulfuric acid. The m-cresol-sulfuric acid mixture was maintained at a temperature of 70° C. and isobutylene was introduced slowly below the surface of the solution. The addition of isobutylene to the reactant mixture was continued until 56 grams of isobutylene had been absorbed. The product thus obtained was washed several times with 10 per cent aqueous sodium hydroxide and refluxed with a small amount of alcoholic KOH to insure complete neutralization of the acid catalyst. The neutralized product was then fractionated at atmospheric pressure through a 15 plate column. The temperature of the column was increased to 180° C. during which time a small amount of polymerized isobutylene was collected. The distillation system was then allowed to cool and placed under a pressure of 20 mm. of mercury. Fractionation was then continued whereby there was obtained a small amount of unreacted m-cresol distilling over at 101° C. and a large amount of 6-tert-butyl-3-methylphenol boiling at 129° to 130° C.

180.4 grams of 6-tert-butyl-3-methylphenol made in accordance with the above procedure, together with 79.0 grams of isopropyl chloride and 200 mls. of carbon disulfide were placed in a 3-neck flask equipped with a stirrer and a reflux condenser. While maintaining the temperature of the contents in the flask at 27° C. 256 grams of zirconium tetrachloride were added in increments of 11.65 grams at 10 minute intervals. The product obtained by this reaction was added to an ice-water mixture and an oily layer separated out. This layer was washed several times with 10 per cent aqueous sodium bicarbonate to remove any hydrogen chloride that might be present. The product was then dried with anhydrous sodium sulfate and charged to a fractionating still having a column equivalent to 15 theoretical plates. After removing the carbon disulfide at atmospheric pressure, the remainder was fractionated into 2 fractions at a pressure of 20 mm. of mercury. The first fraction boiling between 136.8° and 144.4° C. at 20 mm. was made up mainly of di-isopropyl-m-cresols. The second fraction boiling between 151.2° and 157.0° C. at 20 mm. solidified on cooling. This latter fraction was recrystallized from petroleum ether until a solid having a constant melting point was obtained. This solid was a white crystalline material which melted sharply at 115° to 116° C. and was identified as 6-tert-butyl-4-isopropyl-3-methylphenol.

In carrying out the debutylation step, 20.6 grams of 6-tert-butyl-4-isopropyl-3-methyl-

phenol were dissolved in 43.7 grams of benzene. This solution was passed through a 6-inch vertical column of fullers earth maintained at a temperature of 265° C. The theoretical amount of isobutylene was liberated and a clear colorless solution was collected. Benzene was separated from this solution by distillation through a Claisen flask. After all of the benzene was removed, a clear liquid was obtained. This clear liquid was fractionated to give a product determined to be 4-isopropyl-3-methylphenol.

EXAMPLE 3

o-Chlorophenol

Into a flask provided with an agitator were placed 1000 grams of phenol and 50 grams of concentrated sulfuric acid. The phenol-sulfuric acid mixture was maintained at a temperature of 70° C. and isobutylene was introduced slowly below the surface of the solution. The addition of isobutylene was continued until 961 grams of isobutylene had been absorbed. The product thus obtained was refluxed with potassium hydroxide dissolved in absolute alcohol to neutralize the acid catalyst. The neutralized product was then washed with water, dried, and fractionated through a 15 plate column at atmospheric pressure. The temperature of the column was increased up to 190° C. during which time a small amount of tertiary butyl alcohol, water and polymerized isobutylene were collected. The distillation system was then allowed to cool and placed under a pressure of 20 mm. of mercury. Fractionation was then continued whereby there was obtained a small amount each of unreacted phenol and of 4-tert-butylphenol and a large amount of 2,4-di-tert-butylphenol.

103.2 grams of 2,4-di-tert-butylphenol made in accordance with the above procedure, together with 300 mls. of carbon tetrachloride were placed in a 3-neck flask equipped with a stirrer, a reflux condenser and a thermometer. The carbon tetrachloride solution of 2,4-di-tert-butylphenol was maintained at a temperature between about 3° and 6° C. and chlorine was introduced below the surface of the solution. The addition of chlorine to the reactant mixture was continued until 16.2 grams of chlorine were absorbed. The reaction product was then washed with 10 per cent aqueous sodium hydroxide and with water to remove any hydrogen chloride that might be present. The product was then dried with anhydrous sodium sulfate and charged to a distilling flask where most of the carbon tetrachloride was removed by heating on a steam bath. After removing the carbon tetrachloride, the remainder of the product was fractionated through the column equivalent to 5 theoretical plates. The fraction boiling at 148° to 151.2° C. at 20 mm. was determined to be 2,4-di-tert-butyl-6-chlorophenol.

The 2,4-di-tert-butyl-6-chlorophenol obtained as above was then dealkylated by contacting it with fullers earth maintained at a temperature of about 275° C. Isobutylene was liberated and a liquid boiling between 174.5° and 175.8° C. was collected. This liquid was determined to consist mainly of *o*-chlorophenol. There was no evidence of any *p*-chlorophenol being formed.

While I have described my invention herein with respect to various specific examples, it is to be understood that my invention is not limited to

the details of such examples, but may be variously practiced and embodied within the scope of the claims hereinafter made.

I claim:

5. A process for producing a substituted hydroxy aromatic compound which comprises the steps of substituting at least one tertiary alkyl group having from 4 to 12 carbon atoms on the nucleus of an hydroxy aromatic compound capable of exerting a directive influence upon the entering tertiary alkyl group; introducing at least one substituent selected from the group consisting of primary alkyl, secondary alkyl, aryl, aralkyl, acyl, alkenyl, haloalkyl, hydroxyalkyl, alkylaminoalkyl, carboxyalkyl, amino, amido, carbonyl, fluoro, chloro, bromo, iodo, sulfo, hydroxyl, mercapto, cyano, and mercurio radicals into the nucleus of the resulting alkylated hydroxy aromatic compound; and thereafter catalytically dealkylating the resulting substituted alkylated hydroxy aromatic compound at a dealkylation temperature below about 350° C. to remove at least one tertiary alkyl group introduced by the initial step of the process.
10. A process for producing a substituted phenol which comprises the steps of substituting at least one tertiary alkyl group having from 4 to 12 carbon atoms on the nucleus of a phenol capable of exerting a directive influence upon the entering tertiary alkyl group; introducing at least one substituent selected from the group consisting of primary alkyl, secondary alkyl, aryl, aralkyl, acyl, alkenyl, haloalkyl, hydroxalkyl, alkylaminoalkyl, carboxyalkyl, amino, amido, carbonyl, fluoro, chloro, bromo, iodo, sulfo, hydroxyl, mercapto, cyano, and mercurio radicals into the nucleus of the resulting alkylated phenol; and thereafter catalytically dealkylating the resulting substituted alkylated phenol at a dealkylation temperature below about 350° C. to produce a substituted phenol and a free tertiary olefin having from 4 to 12 carbon atoms.
15. A process for producing a substituted phenol which comprises the steps of substituting at least one tertiary butyl group on the nucleus of a phenol capable of exerting a directive influence upon the entering tertiary butyl group; introducing at least one substituent selected from the group consisting of primary alkyl, secondary alkyl, aryl, aralkyl, acyl, alkenyl, haloalkyl, hydroxyalkyl, alkylaminoalkyl, carboxyalkyl, amino, amido, carbonyl, fluoro, chloro, bromo, iodo, sulfo, hydroxyl, mercapto, cyano, and mercurio radicals into the nucleus of the resulting alkylated phenol; and thereafter catalytically dealkylating the resulting substituted alkylated phenol at a dealkylation temperature below about 350° C. to remove at least one tertiary butyl group introduced by the initial step of the process.
20. A process for producing a substituted phenol which comprises the steps of substituting at least one tertiary butyl group on the nucleus of a phenol capable of exerting a directive influence upon the entering tertiary butyl group; introducing at least one substituent selected from the group consisting of primary alkyl, secondary alkyl, aryl, aralkyl, acyl, alkenyl, haloalkyl, hydroxalkyl, alkylaminoalkyl, carboxyalkyl, amino, amido, carbonyl, fluoro, chloro, bromo, iodo, sulfo, hydroxyl, mercapto, cyano, and mercurio radicals into the nucleus of the resulting alkylated phenol; and thereafter catalytically dealkylating the resulting substituted alkylated phenol at a dealkylation temperature below about 350° C. to produce a substituted phenol and a free tertiary olefin having from 4 to 12 carbon atoms.
25. A process for producing a substituted phenol which comprises the steps of substituting at least one tertiary butyl group on the nucleus of a phenol capable of exerting a directive influence upon the entering tertiary butyl group; introducing at least one substituent selected from the group consisting of primary alkyl, secondary alkyl, aryl, aralkyl, acyl, alkenyl, haloalkyl, hydroxalkyl, alkylaminoalkyl, carboxyalkyl, amino, amido, carbonyl, fluoro, chloro, bromo, iodo, sulfo, hydroxyl, mercapto, cyano, and mercurio radicals into the nucleus of the resulting alkylated phenol; and thereafter catalytically dealkylating the resulting substituted alkylated phenol at a dealkylation temperature below about 350° C. to remove at least one tertiary butyl group introduced by the initial step of the process.
30. A process for producing a substituted phenol which comprises the steps of substituting at least one tertiary butyl group on the nucleus of a phenol capable of exerting a directive influence upon the entering tertiary butyl group; introducing at least one substituent selected from the group consisting of primary alkyl, secondary alkyl, aryl, aralkyl, acyl, alkenyl, haloalkyl, hydroxalkyl, alkylaminoalkyl, carboxyalkyl, amino, amido, carbonyl, fluoro, chloro, bromo, iodo, sulfo, hydroxyl, mercapto, cyano, and mercurio radicals into the nucleus of the resulting alkylated phenol; and thereafter catalytically dealkylating the resulting substituted alkylated phenol at a dealkylation temperature below about 350° C. to produce a substituted phenol and a free tertiary olefin having from 4 to 12 carbon atoms.
35. A process for producing a substituted phenol which comprises the steps of substituting at least one tertiary butyl group on the nucleus of a phenol capable of exerting a directive influence upon the entering tertiary butyl group; introducing at least one substituent selected from the group consisting of primary alkyl, secondary alkyl, aryl, aralkyl, acyl, alkenyl, haloalkyl, hydroxalkyl, alkylaminoalkyl, carboxyalkyl, amino, amido, carbonyl, fluoro, chloro, bromo, iodo, sulfo, hydroxyl, mercapto, cyano, and mercurio radicals into the nucleus of the resulting alkylated phenol; and thereafter catalytically dealkylating the resulting substituted alkylated phenol at a dealkylation temperature below about 350° C. to produce a substituted phenol and a free tertiary olefin having from 4 to 12 carbon atoms.
40. A process for producing a substituted phenol which comprises the steps of substituting at least one tertiary butyl group on the nucleus of a phenol capable of exerting a directive influence upon the entering tertiary butyl group; introducing at least one substituent selected from the group consisting of primary alkyl, secondary alkyl, aryl, aralkyl, acyl, alkenyl, haloalkyl, hydroxalkyl, alkylaminoalkyl, carboxyalkyl, amino, amido, carbonyl, fluoro, chloro, bromo, iodo, sulfo, hydroxyl, mercapto, cyano, and mercurio radicals into the nucleus of the resulting alkylated phenol; and thereafter catalytically dealkylating the resulting substituted alkylated phenol at a dealkylation temperature below about 350° C. to produce a substituted phenol and a free tertiary olefin having from 4 to 12 carbon atoms.
45. A process for producing a substituted phenol which comprises the steps of substituting at least one tertiary butyl group on the nucleus of a phenol capable of exerting a directive influence upon the entering tertiary butyl group; introducing at least one substituent selected from the group consisting of primary alkyl, secondary alkyl, aryl, aralkyl, acyl, alkenyl, haloalkyl, hydroxalkyl, alkylaminoalkyl, carboxyalkyl, amino, amido, carbonyl, fluoro, chloro, bromo, iodo, sulfo, hydroxyl, mercapto, cyano, and mercurio radicals into the nucleus of the resulting alkylated phenol; and thereafter catalytically dealkylating the resulting substituted alkylated phenol at a dealkylation temperature below about 350° C. to produce a substituted phenol and a free tertiary olefin having from 4 to 12 carbon atoms.
50. A process for producing a substituted phenol which comprises the steps of substituting at least one tertiary butyl group on the nucleus of a phenol capable of exerting a directive influence upon the entering tertiary butyl group; introducing at least one substituent selected from the group consisting of primary alkyl, secondary alkyl, aryl, aralkyl, acyl, alkenyl, haloalkyl, hydroxalkyl, alkylaminoalkyl, carboxyalkyl, amino, amido, carbonyl, fluoro, chloro, bromo, iodo, sulfo, hydroxyl, mercapto, cyano, and mercurio radicals into the nucleus of the resulting alkylated phenol; and thereafter catalytically dealkylating the resulting substituted alkylated phenol at a dealkylation temperature below about 350° C. to produce a substituted phenol and a free tertiary olefin having from 4 to 12 carbon atoms.
55. A process for producing a substituted phenol which comprises the steps of substituting at least one tertiary butyl group on the nucleus of a phenol capable of exerting a directive influence upon the entering tertiary butyl group; introducing at least one substituent selected from the group consisting of primary alkyl, secondary alkyl, aryl, aralkyl, acyl, alkenyl, haloalkyl, hydroxalkyl, alkylaminoalkyl, carboxyalkyl, amino, amido, carbonyl, fluoro, chloro, bromo, iodo, sulfo, hydroxyl, mercapto, cyano, and mercurio radicals into the nucleus of the resulting alkylated phenol; and thereafter catalytically dealkylating the resulting substituted alkylated phenol at a dealkylation temperature below about 350° C. to produce a substituted phenol and a free tertiary olefin having from 4 to 12 carbon atoms.
60. A process for producing 2,6-dichlorophenol which comprises alkylating phenol with isobutylene to form 4-tertiary-butylphenol, chlorinating said 4-tertiary-butylphenol to form the corresponding 2,6-dichloro-4-tertiary-butylphenol, and thereafter catalytically dealkylating said 2,6-dichloro-4-tertiary-butylphenol at a dealkylation temperature below about 350° C. to form 2,6-dichlorophenol.
65. A process for producing 2,6-dichlorophenol which comprises alkylating phenol with isobutylene to form 4-tertiary-butylphenol, chlorinating the resulting 2,4-di-tertiary-butylphenol to form the corresponding 2,4-di-tertiary-butyl-6-chlorophenol, and thereafter catalytically dealkylating the resulting 2,4-di-tertiary-butyl-6-chlorophenol at a dealkylation temperature below about 350° C. to form 2,6-dichlorophenol.
70. A process for producing ortho-chlorophenol which comprises alkylating phenol with isobutylene to form 2,4-di-tertiary-butylphenol, chlorinating the resulting 2,4-di-tertiary-butylphenol to form the corresponding 2,4-di-tertiary-butyl-6-chlorophenol, and thereafter catalytically dealkylating the resulting 2,4-di-tertiary-butyl-6-chlorophenol at a dealkylation temperature below about 350° C. to form 2,4-di-tertiary-butyl-6-chlorophenol.
75. A process for producing ortho-chlorophenol which comprises alkylating phenol with isobutylene to form 2,4-di-tertiary-butylphenol, chlorinating the resulting 2,4-di-tertiary-butylphenol to form the corresponding 2,4-di-tertiary-butyl-6-chlorophenol, and thereafter catalytically dealkylating the resulting 2,4-di-tertiary-butyl-6-chlorophenol at a dealkylation temperature below about 350° C. to form 2,4-di-tertiary-butyl-6-chlorophenol.

17

chlorophenol at a dealkylation temperature below about 350° C. to form ortho-chlorophenol.
DONALD R. STEVENS.
